SOAP BOX HOLDER

Sophie Mandich, 7016 S. 30th St., Omaha, Nebr.
Filed May 11, 1961, Ser. No. 109,398
1 Claim. (Cl. 220—85)

This invention relates to soap box holders and more particularly it is an object of this invention to provide a soap box holder which can be held with wet, and sometimes soapy hands, more easily than soap box holders of the prior art.

A common problem has been that granulated soap boxes are handled with wet hands whereby the glue comes apart and the soap spills out on the floor as is frustratingly common.

Also soap boxes are often set on the top of a wet table or wet washing machine surface whereby the glue on the bottom of such boxes quickly loosens and the soap spills out.

It is my belief that it is because of the absence from the market of a generally available soap box holder that the liquid detergents have come into greater use, even though some of the latter are more expensive.

The cardboard soap boxes deform quickly even when they do not break because they are easily pressed in when partially empty and they soon become dilapidated and unsightly from being handled with wet hands. Other attempts to solve this problem have not met with general acceptance.

I am aware that others have heretofore proposed soap boxes formed of plastic or the like, however, these have always had disadvantages. A chief disadvantage has been the absence of suitable means on the box holder to facilitate gripping it as plastic, held in soapy hands, is even more slippery than cardboard.

I am aware that a knurled criss-cross rough surface has been proposed for the wall of a milk carton holder. But while this may be sufficient for milk or an item carried when the hands are dry, it cannot solve the problem for items carried with wet soapy hands.

It is, therefore, an object of this invention to provide a concept of adequate means to prevent the soap box from slipping out of the hands as no means has ever been proposed for soap boxes by the prior art.

The second disadvantage of soap boxes of the prior art is that they have been designed as dispensing containers whereby they have had closeable openings through which soap is poured. This has led to unnecessary expense and it is my belief that this expense has been a contributing factor to the unavailability of these soap box containers and their absence from broad general use.

The concept of making the soap box container into a dispenser has led to extra cost, not only from necessity of a moveable closure means, but also from the need to cover the top part of the soap box so that dispensed soap must pass through a box container dispensing port. It is an object of this invention to provide a concept of a simplicity of a soap box holder without a costly top whereby the holder can be marketed at a price leading to mass production and general availability.

Soap boxes can always be opened to a limited extent for controlled dispensing whereby the soap box itself is a dispenser whereby it is my concept that it is wasteful and that there is no need to provide a dispenser to contain a dispenser.

Soap boxes are usually printed with various recipes, housekeeping suggestions, and other interesting information continually being varied by the manufacturers. The only soap boxes heretofore proposed have been formed of opaque containers and it is an object of this invention to provide a soap box container which is formed of transparent material.

2

A further object is to provide a specific and adequate means for preventing soap boxes from slipping out of wet soapy hands, such means being much different and more extensive than has been proposed for milk carton containers.

5 A still further object is to provide a soap box container with a ridge extending vertically down the side, across which the fingers extend such that, in effect, the container is wider in the portion of the container that is gripped and whereby ledge means is provided around which the fingers can extend for the effective control of a slippery soap box.

10 Still another object is to provide a soap box container which has spaced protrusions extending outwardly from its side, the protrusions being extensive enough to be effectively gripped by fingers to prevent the slipping away of the container.

15 A further object is to provide a soap box container, the gripping surfaces of which are achieved by means of spaced openings extending deep into and preferably through the soap box container whereby it is controllable.

20 Other and further objects and advantages of the present invention will be apparent from the following detailed description, drawings and claim, the scope of the invention not being limited to the drawings themselves as the drawings are only for the purpose of illustrating a way in which the principles of this invention can be applied.

25 Other embodiments of the invention utilizing the same or equivalent principles may be used and structural changes may be made as desired by those skilled in the art without departing from the present invention and the purview of the appended claim.

In the drawings:

30 FIGURE 1 is a side elevation of a soap box which is received in a soap box container of this invention.

35 FIGURE 2 is a top plan view of a modification of the container of FIGURE 1 in which upright outwardly protruding portions facilitate gripping the container.

40 FIGURE 3 is a sectional view taken along line 3—3 of FIGURE 2.

45 FIGURE 4 is a side elevation of a modification of this invention in which the container has spaced openings to facilitate gripping the container.

50 FIGURE 5 is a side elevation of a modification of the invention in which the container has spaced protrusions on the side thereof for facilitating gripping of the container.

55 FIGURE 6 is a sectional view taken along line 6—6 of FIGURE 5.

50 Referring to FIGURE 1, it will be seen that the soap box container of this invention is generally shown at 10 having side walls 12, a bottom wall 14, as seen in FIGURE 2, two of the side walls 12 actually being end walls 16 since the general shape of the side wall configuration is rectangular to fit closely to a common soap box 18, having a pouring spout 20.

55 The bottom wall 14 having an under surface which is adapted to hold the upper side of the bottom wall horizontal for holding the soap box 18 upright when the bottom of the container is rested on a horizontal surface.

60 The container 10 has an open upper end into which a soap box can be placed. The upper edge 28 of the container 10 is preferably disposed at a height substantially below the top of the soap box for economy of material and manufacture. The material used is preferably of a transparent plastic so that printed matter as indicated at 30 on the soap box 18 can be seen therethrough.

65 Such printed matter can be instructions, advice, soap box top premiums, and various other items normally printed on a soap box and it is important that all of these can be read through the soap box. Sometimes this advice is a cooking recipe.

The container can have some means thereon for facilitating the effective maintenance of a hand-grip at times when the hands and the box are slippery with soap solution as is common. A preferred form of such means is shown in FIGURE 2 in which the soap box has at least one outwardly offset protruding portion 40 protruding outwardly from the side of the container for providing a ledge 42 which is disposed extending upright with respect to the container and against which the fingers 50 can be engaged for the firm holding of the box.

It will be seen in FIGURE 2 that the protruding portion 40 does not extend outwardly from the adjacent side of the box substantially more than the minimum necessary for gripping of the box by the extended fingers of the hand of the operator.

It will be seen that because the container is made of plastic, and in order to hold the shape making the ledges 42 meaningful, the container must and does have a construction sufficiently rigid as to substantially hold its shape when gripped by the operator's hand. In this way it is distinguished from mere lapping materials as it is a super-sustaining plastic container.

FIGURE 4 shows a modified container 12" having spaced openings 54 through sides thereof to facilitate gripping the container.

FIGURE 5 shows a modified container 13 having a plurality of spaced protrusions 60 spaced outwardly from the sides thereof for facilitating gripping the container. The protrusions 60 will be found to make it possible to grip container 13 much more firmly when its surfaces are slippery with soapy water.

From the foregoing description, it is thought to be obvious that a soap box holder constructed in accordance with my invention is particularly well adapted for use, by reason of the convenience and facility with which it may be assembled and operated, and it will also be obvious that my invention is susceptible of some change and modifica-

tion without departing from the principles and spirit thereof, and for this reason, I do not wish to be understood as limiting myself to the precise arrangement and formation of the several parts herein shown in carrying out my invention in practice, except as claimed.

5 I claim:

A soap box container of oblong rectangular shape in horizontal cross section having side walls and a bottom wall and being adapted to receive and support a soap box 10 above a surface on which the container is rested, said container having an open upper end through which the upper portion of the soap box can extend whereby the container can be economically manufactured, said container further having means thereon sufficient for the effective 15 maintenance of a hand grip at times when the hands and box are slippery with soap solution, and said container being sufficiently rigid so as to substantially hold its shape when gripped by an operator's hand, said means for facilitating gripping of said box comprising at least one offset portion protruding outwardly from said container, said offset portion not protruding outwardly from the container substantially greater than the minimum necessary for gripping by the extended fingers, said offset portion providing a ledge extending upright with respect to the container against which the fingers can be engaged to firmly hold the box.
